UNITED STATES PATENT OFFICE.

LOUIS J. MONAHAN, OF OSHKOSH, WISCONSIN.

DESIGN FOR A BODY FOR NUT-CUTTING MACHINES.

45,268.

Specification for Design.

Patented Feb. 17, 1914.

Application filed August 2, 1913. Serial No. 782,727. Term of patent 7 years.

To all whom it may concern:

Be it known that I, LOUIS J. MONAHAN, a citizen of the United States, residing at Oshkosh, in the county of Winnebago and State of Wisconsin, have invented a new, original, and ornamental Design for a Body for Nut-Cutting Machines, of which the following is a specification, reference being had to the accompanying drawing, forming part thereof.

The figure is a side view of the body for nut cutting machine as it would stand when

attached to a counter, shelf, table, etc., and is especially adapted to the use of soda fountains when it forms an ornament in connection with trimmings thereof.

I claim:

The ornamental design for a body for nut cutting machines, as shown.

LOUIS J. MONAHAN.
